UNITED STATES PATENT OFFICE.

EDWARD B. CARTER, OF BOSTON, MASSACHUSETTS.

STRINGING MACHINE.

Application filed April 23, 1927. Serial No. 186,125.

My present invention is a novel and improved machine for use in stringing articles on wires or similar devices, being particularly adapted to string such articles having 5 perforations therein.

The present machine is particularly advantageous in the stringing of washers of the type used in the manufacture of rubber heels, and will function equally well with 10 either flat or concave washers.

It has heretofore been considered impossible to string such concave washers upon wires, with the convex surface of said washers down. The practice today, in the few 15 machines feasible for this work, is to string concave washers with the concave surface down or toward the closed end of the wire. This necessitates a transfer of the thus strung washers to a second wire, in order 20 that the washers may be then positioned or strung convex face down or toward the closed end of the wire. From this last strung position, the washers are shipped to the factories manufacturing rubber heels, 25 and are there transferred from the second wires to third wires, in the washer placing machines. All of these operations necessarily involve time and expense, and are otherwise disadvantageous.

30 My present novel machine obviates the difficulties above pointed out by stringing the washers upon the wires, in nested relation, and with the convex sides of the washers facing downwardly on the wires on which 35 they are strung.

I accomplish this desirable result by means of an exceedingly simple machine, having in essence but one moving part. This machine comprises a hopper, through which is 40 moved a rotor. In the rotor are a plurality of inserts having initial washer receiving recesses or paths. Provided at predetermined spaced intervals over the surface of the rotor and inserts are a plurality 45 of concentric guideways, interrupted at predetermined spaced intervals by pockets in said inserts. A plurality of wires are provided at one side of the machine, in such a position as to have their points or ends engage 50 said concentric guideways. On movement of the rotor through the hopper, and through the stack or pile of washers contained in said hopper, washers will be received in the recesses provided in the inserts. The rotor is inclined, and the washers 55 are received in said recesses concave face

down. Movement of the rotor being continued, when the inserts have passed top center of the rotor and are on their downward path, the washers will slide along said recesses, and drop into the pockets above mentioned, and will be held in said pockets with the perforations in the washers presented to the respective concentric guideways. The washers as thus held in the 60 pockets, are presented to the points of the wires convex side down, so that they will be fed to the wires and nested thereon in position ready for shipment, or for use in washer placing machines, without the necessity of 65 subsequently transferring the washers to an intermediate wire before final use.

The wires in my present machine are held in spring controlled sockets, so that when the wires are filled they will not present 70 resistance to the passage of the rotor over said wires, the spring held sockets permitting the wires to "give" as pressure is exerted thereon, as for instance by bad washers, and thus the operation of the machine will not be 75 impeded, and no damage will be caused to the machine or the wires. Suitable guideways and retaining means are provided for the wires, to maintain said wires in correct 80 alignment and position.

85 A complementary hopper is provided into which excess washers, or washers which are carried by the rotor when the wires are removed from the machine, will fall, and will return to the main hopper.

90 I believe that my machine, as above briefly outlined, is novel, and I have therefore claimed the same broadly herein.

95 Further features of the invention, details of construction, combinations of parts, and advantages, will be hereinafter more fully pointed out and claimed.

100 Referring to the drawings, illustrating a preferred embodiment of the present invention,

Fig. 1 is a side elevation of the machine;

Fig. 2 is a front elevation of a portion of the machine;

Fig. 3 is a sectional view on the line 3—3 of Fig. 1;

Fig. 4 is a cross sectional view of a portion of the rotor and insert at the lowermost point of the rotor;

Fig. 5 is a cross sectional view on the line 5—5 of Fig. 3;

Fig. 6 is a sectional view on the line 6—6 of Fig. 3;

Fig. 7 is a plan view of one of the inserts and a portion of the rotor;

Fig. 8 is a cross sectional view on the line 8—8 of Fig. 3;

5 Fig. 9 is a plan view of the part shown in Fig. 8;

Fig. 10 is a cross sectional view illustrating the position of wires and washers just prior to positioning of the washers on the wires;

10 Fig. 11 is a cross sectional view on the line 11—11 of Fig. 3; and

Fig. 12 is a cross sectional view on the line 12—12 of Fig. 2.

As shown in the drawings, my present 15 novel machine comprises a hopper consisting of side walls 1 and 2, inclined base 3, front wall 4, and back wall 5. The side walls 1 and 2 depend below the base 3 and act as a support for the hopper resting on a 20 bench or base 6. A stack of washers is illustrated generally at 7. Mounted to move through the hopper and the stack of washers, is a rotor 8. This rotor is provided around its periphery with a circumferential slot or 25 groove 9, in which slot the back wall 5 of the hopper fits. This serves both as a guide and supporting means for the rotor, and also prevents the washers in the hopper falling out of the back of the hopper. At 11, 11 is

30 clearly illustrated the manner in which the back wall 5 engages the groove 9. The rotor 8 has a hub 12 through which passes a shaft 13. This shaft 13 is mounted in a bearing 14, and is secured against longitudinal movement by a disc or washer 15 pinned to the shaft 13 as at 16. The shaft 13 is secured to the hub 12 by a pin or the like 17, and an anti-friction bearing 18 is interposed between the hub 12 and the main bearing 14.

40 This main bearing 14 is a part of a standard or support 19 having a face 20. Secured to the back of the rotor 8 by screws or the like 21 is a ring gear 22, meshing with a gear 23 on the shaft 24, said shaft being held in a

45 suitable bearing 25 also carried by the standard 19. The shaft 24 is driven by a gear 25, which is in turn rotated by a worm 26, said worm being attached to a pulley or the like 27 to which power is transmitted by

50 a belt or other driving means 28. A bearing 29 for the lower or reduced portion 30 of the shaft 24 is provided, a supporting frame 31 therefor being secured to the standard 19. Set in the rotor 8 are a plurality

55 of inserts 32, these inserts being plate members with their upper surfaces flush with the upper or front surface of the rotor. These inserts 32 are formed with bevelled edges 33, and are inserted in undercut recesses 34 in the rotor. At the outer end the

60 inserts 32 are secured to the rotor 8 by screws 35, and are held in position at their inner end by a ring 36 secured to the rotor by means of screws 37. The ring 36 has a flange or shoulder 38 engaging a corre-

sponding flange or shoulder 39 on the inserts 32, thus securely holding the inner ends of the inserts.

The rotor 8 and inserts 32 are provided with a plurality of concentric guideways 70 40, and the inserts 32 are each provided with a plurality of recesses 41, the guideways 40 passing through approximately the center of said recesses. Each recess, as clearly shown in Fig. 7, for example, has an end 75 wall 42 and side walls 43, to confine the washer, illustrated at 44, within the recess 41. The rotor 8 is set in an inclined position, at all times, and it will be understood that as the rotor moves through the stack 80 of washers, illustrated at 7, certain of said washers will enter the recesses 41 in the inserts 32, the walls of said recess being of such a height that only those washers which are received with their concave sides against 85 the rotor will be retained in said recesses. As shown in Fig. 3, these washers 44 will all be held against the end walls 42 of the recesses 41, until the inserts have passed top center during rotation of the rotor. After 90 thus passing top center, the force of gravity will slide the washers 44 along the recesses 41 until they drop, of their own weight, over the rounded edges 45 at the ends of the recesses 41, and into pockets 46. These 95 pockets 46 are so constructed and arranged that the washers can only be received therein with their convex sides presented toward the path of movement of the rotor. The washers 44, thus held in pockets 46, are 100 also so positioned that the perforations 47 in said washers are presented to the concentric guideways 40. A small chute 48 secured to the side wall 2 is provided, said chute being inclined toward the main hopper, and into which chute any washers which 105 do not drop into the pockets 46 will drop, and be conveyed to the main hopper.

A plurality of wires 50 are positioned in such manner that the upper end or point of each wire will engage one of the concentric guideways 40. These wires are alined by guides 51, secured to a frame 52, which frame is in turn secured to the side wall 2 as shown at 53, 53. A pivoted guiding and spacing member 54 is provided adjacent to the upper ends of the wires 50, to prevent springing of the wires outwardly. At the lower end of the frame 52 is affixed a compartment 55, in which compartment are positioned a plurality of plungers 56, each plunger having a socket 57 and a slight stem 58 to engage one end of a coiled spring 59, the other end of the coiled spring 59 resting against the bottom of the compartment 55. Slots 60 are provided in the inner wall of the compartment 55, and a pin 61, secured to each plunger 56, rides in these slots 60, and is guided thereby. Each of the wires 50 are provided at their lower ends 115 120 125 130

with an enlarged portion or button 62, of greater diameter than the perforations 47 in the washers 44. A rest or rod 63 is provided, for the strung wires, to prevent warping or springing thereof.

A complementary hopper, illustrated generally at 64, extends outwardly from the main hopper, and is adapted to receive any washers which may miss the wires, or otherwise fall from the rotor, from which complementary hopper the washers will mingle with the washers in the main hopper.

Figs. 4, 5, 8, 10 and 11 illustrate graphically the operation of the present machine.

15 In Fig. 4 an insert 32 is at its lowermost point in the hopper, and a washer 44 has been received in the recess 41, with its concave side toward the insert. In Fig. 5 the insert is part way up beyond the stack of 20 washers, and the washer 44 has dropped down against the edge 42 of the recess 41. In Fig. 8 the insert 32 has passed top center, these inserts moving in the direction of the arrows. The washer 44 has dropped, by 25 gravity, over the curved edge 45 of the recess, and into the pocket 46. As shown in Fig. 10, the perforation 47 is then in alignment with the guideway 40, and the wire 50 following this guideway has its point presented to the perforation 37. The rotor continuing its movement, the washer 44 is positioned on to the wire, as clearly shown in Fig. 11. The washers 44 will now drop along the wires 50, as shown in Figs. 1 and 2. When the wires are filled, the last washer will ride upon the point of the wire 50, raising the point from the rotor and inserts so that no damage will result thereto, and upon the top washer striking any of the 45 pockets 46, or other obstructions, the wire will be pushed downwardly, and the spring 59 will permit giving of the wire so that the operation of the machine will not be retarded, and no damage will be caused to the machine, wires, or washers. The springs 59 will also function in this manner, should an imperforate or faulty washer be presented to the wires, depressing the wire from washer receiving position without bending the same, and permitting the imperfect washer to drop beyond the wire.

It will thus be seen that I have devised an extremely simple, economical, and efficient machine for this purpose. This machine will operate equally as well with flat washers as with concavo-convex washers. If desired, the pockets 46 may be made of a sufficient size to accommodate more than one washer at a time, which will increase the speed of the stringing operation, particularly with flat washers. Also, while I have described and shown the present machine as working on and stringing washers, it will be appreciated that it is equally as applicable to other articles, and it is not

my intention to limit the machine of the present invention to washers.

While I have necessarily described my present invention somewhat in detail, it will be appreciated that I may vary the size, 70 shape, and arrangement of parts, within reasonably wide limits, without departing from the spirit of the invention.

One of the very important features of the present invention is the capacity of my novel machine for the selecting, positioning, and feeding of articles directly from a mass or pile, by means moving in an angular position and acting substantially as a part of one wall of the magazine or hopper containing said mass of articles. While this invention is primarily intended to handle, feed, position, and string such articles as washers or the like, it is also capable of use with eyelets, grommets, or such devices, particularly where a predetermined position of the articles being handled is desired. For example, in operating upon eyelets, the machine as described herein would be identical up to and including the wires, and from the wires the eyelets may be fed into chutes, delivered in proper stacked or nested relation for subsequent use. It will, therefore, be appreciated that my present machine is not restricted to merely stringing articles, 95 but is more broadly adapted, and has a wide field of utility.

My invention is further described and defined in the form of claims as follows:

1. In a washer stringing machine, a washer carrying rotor, a wire associated with said rotor, and means to present the convex side of said washers to one end of said wire. 100

2. In a washer stringing machine, a washer carrying rotor, a wire engaging the face of said rotor, and means to present the convex side of said washers to one end of said wire. 105

3. In a washer stringing machine, a washer carrying rotor having an annular guideway thereon, a wire engaging said guideway, 110 and means to present the convex side of said washers to one end of said wire.

4. In a stringing machine, a rotor having a plurality of concentric guideways on one face thereof and having article engaging pockets alined with said guideways, a plurality of wires for receiving said articles, and means to cause relative movement between said rotor and said wires. 115

5. In a stringing machine, a rotor having a plurality of concentric guideways on one face thereof and having article engaging pockets alined with said guideways, a plurality of wires engaging said guideways for receiving said articles, and means to cause relative movement between said rotor and said wires. 120

6. In a stringing machine, a rotor, an insert in said rotor having article engaging pockets therein, said rotor and said insert 130

- having an annular guideway thereon, a wire engaging said guideway to receive said articles, and means to cause relative movement between said rotor and said wire.
- 5 7. In a stringing machine, a rotor, a plurality of inserts in said rotor having article engaging pockets therein, said rotor and said inserts having an annular guideway thereon, a wire engaging said guideway to receive 10 said articles, and means to cause relative movement between said rotor and said wire.
- 15 8. In a stringing machine, a rotor, a plurality of inserts in said rotor having article engaging pockets therein, said rotor and said inserts having a plurality of concentric guideways thereon, a plurality of wires engaging said guideways to receive said articles, and means to cause relative movement between said rotor and said wires.
- 20 9. In a stringing machine, a rotor having a plurality of article engaging recesses therein, and having a plurality of pockets adjacent to said recesses, said articles passing, during continued rotation of said rotor, 25 from said recesses into said pockets, a wire positioned in alinement with said pockets, and means to cause relative movement between said rotor and said wire.
- 30 10. In a stringing machine, a rotor, a wire, and means to cause relative movement between said rotor and said wire, said rotor having article engaging recesses and pockets adapted to receive articles therein and to 35 present the convex side of successive articles to said wire to be strung thereon during said relative movement.
- 40 11. In a stringing machine, a rotor, a plurality of inserts in said rotor having article engaging recesses and pockets therein, said rotor and inserts having an annular guideway thereon, a wire, and means to cause relative movement between said rotor and said wire, the point of said wire being in 45 continuous engagement with said guideway and in alinement with said pockets to remove said articles from said pockets during said relative movement.
- 50 12. In a stringing machine, a rotor, a plurality of inserts in said rotor having article engaging recesses and pockets therein, said rotor and inserts having a plurality of concentric guideways thereon, wires positioned in engagement with said guideways and in alinement with said pockets, and means to 55 cause relative movement between said rotor and said wires.
- 60 13. A stringing machine comprising a hopper, a rotor having washer engaging pockets therein and movable through said hopper to receive washers in said pockets, a wire positioned in alinement with said pockets, means to cause relative movement between said rotor and said wire, said pockets being so constructed that only washers 65 which will have their convex side presented to said wire during said relative movement will be received therein.
14. A stringing machine comprising a hopper, a rotor having article engaging pockets therein and movable through said hopper to receive articles in said pockets, a plurality of concentric guideways on said rotor, wires engaging said guideways, and means to cause relative movement between said rotor and said wires to aline said 75 pockets with said wires and deliver said articles thereto. 70
15. A stringing machine comprising a hopper, a rotor having article engaging pockets therein and movable through said hopper to receive articles in said pockets, a plurality of concentric guideways on said rotor, spring-controlled wires engaging said guideways, and means to cause relative movement between said rotor and said wires to aline said 80 pockets with said wires and deliver said articles thereto. 85
16. A stringing machine comprising a hopper, a rotor having article engaging pockets therein and movable through said hopper to receive articles in said pockets, a plurality of concentric guideways on said rotor, spring-controlled wires engaging said guideways, means to cause relative movement between said rotor and said wires to aline said 90 pockets with said wires and deliver said articles thereto, and means to space, support, and aline said wires. 95
17. A stringing machine comprising a hopper, a rotor having article engaging pockets therein and movable through said hopper to receive said articles in said pockets, a plurality of concentric guideways on said rotor, wires engaging said guideways, means to cause relative movement between said rotor and said wires to aline said 100 pockets with said wires and deliver said articles thereto, said rotor being provided with a peripheral groove, and one wall of said hopper being formed to engage said groove. 105
18. In a stringing machine, a rotor, a plurality of inserts in said rotor having article engaging recesses and pockets therein, said rotor and inserts having a plurality of concentric guideways thereon, wires positioned in engagement with said guideways and in alinement with said pockets, means to cause relative movement between said rotor and said wires, and means on said rotor to hold said inserts against movement. 110
19. In a stringing machine, a rotor, a plurality of inserts in said rotor having article engaging recesses and pockets therein, said rotor and inserts having a plurality of concentric guideways thereon, wires positioned in engagement with said guideways and in alinement with said pockets, and a removable ring on said rotor to hold said inserts against movement. 115
20. In a machine of the kind described, a 120

- hopper adapted to hold a quantity of rotor, wires engaging said guideways, means to cause relative movement between said rotor and said wires to aline said pockets with said wires and deliver said articles thereto, said wires resting in spring controlled members. 70
21. In a stringing machine, a rotor having a plurality of article engaging recesses 10 therein, and having a plurality of pockets adjacent to said recesses, means to rotate said rotor, said recesses and said pockets being so constructed and arranged that said articles will pass from said recesses into said pockets during continued rotation of said rotor. 73
22. In a stringing machine, a rotor having a plurality of article engaging recesses therein, and having a plurality of pockets 15 adjacent to said recesses, means to rotate said rotor, said recesses and said pockets being so constructed and arranged that said articles will pass from said recesses into said pockets during continued rotation of said rotor, and means to remove said articles from said pockets. 80
23. In a stringing machine, a rotor, a plurality of inserts in undercut grooves in 20 said rotor, said inserts having article engaging recesses and pockets therein, said rotor and inserts having a plurality of concentric guideways thereon, wires positioned in engagement with said guideways, and means to cause relative movement between said rotor 25 and said wires to aline said pockets with said wires and deliver said articles thereto. 90
24. In a washer stringing machine, a washer carrying rotor having an annular guideway thereon, a wire, and means to position washers on said wire, the point of said wire being in continuous engagement with said guideway until the stringing of said wire is completed. 100
25. In a washer stringing machine, a washer carrying rotor having an annular guideway thereon, a wire, and means to present the convex sides of said washers to said wire, the point of said wire being in continuous engagement with said guideway 105 until the stringing of said wire is completed. 110
26. In a stringing machine, a rotor having a plurality of concentric guideways on one face thereof and having article retaining pockets alined with said guideways, a plurality of wires, the points only of said wires engaging said guideways to receive said articles, and means to cause relative movement between said rotor and said wires. 115
27. A stringing machine comprising a hopper, a rotor having article engaging pockets therein and movable through said hopper to receive articles in said pockets, a plurality of concentric guideways on said 120
28. A stringing machine comprising a hopper, a rotor having article engaging pockets therein and movable through said hopper to receive articles in said pockets, a plurality of concentric guideways on said rotor, wires engaging said guideways, means to cause relative movement between said rotor and said wires to aline said pockets with said wires and deliver said articles thereto, said wires resting in spring controlled members, and means to limit the movement of said spring controlled members and said wires. 85
29. A stringing machine comprising a hopper, a rotor having article engaging pockets therein and movable through said hopper to receive articles in said pockets, a plurality of concentric guideways on said rotor, wires engaging said guideways, means to cause relative movement between said rotor and said wires to aline said pockets with said wires and deliver said articles thereto, a casing, and a plurality of spring controlled hollow plungers in said casing, said wires 95 resting in said plungers. 95
30. A stringing machine comprising a hopper, a rotor having article engaging pockets therein and movable through said hopper to receive articles in said pockets, a plurality of concentric guideways on said rotor, wires engaging said guideways, means to cause relative movement between said rotor and said wires to aline said pockets with said wires and deliver said articles thereto, a casing, a plurality of hollow plungers in said casing, springs bearing against said plungers, said wires resting in said plungers, and means to limit the movement of said plungers and said wires. 100 105
31. A stringing machine comprising a hopper, a rotor having article engaging pockets therein and movable through said hopper to receive articles in said pockets, a plurality of concentric guideways on said rotor, wires engaging said guideways, means to cause relative movement between said rotor and said wires to aline said pockets with said wires and deliver said articles thereto, a casing, a plurality of hollow plungers in said casing, springs bearing against said plungers, said wires resting in said plungers, said casing having a plurality of slots therein, a stud on each of said plungers engaging said slots to 110 limit the movement of said plungers and said wires. 115
32. In a washer stringing machine, a washer carrying rotor, a wire associated with said rotor, and means to present the 120

convex surfaces of said washers to one end of said wire.

33. In a washer stringing machine, a washer carrying rotor, a wire associated with 5 said rotor, means to position washers on said wire, a casing, a hollow plunger in said casing, said wire resting in said plunger, and means to limit the movement of said plunger.

10 34. In a washer stringing machine, a washer carrying rotor, a wire associated with said rotor, means to position washers on said wire, a casing, a hollow plunger in said casing, a spring bearing against said 15 plunger, said wire resting in said plunger, and means to limit the movement of said plunger and said wire.

35. In a washer stringing machine, a washer carrying rotor, a wire associated with 20 said rotor, means to position washers on said wire, a casing, a hollow plunger in said casing, a spring bearing against said plunger, said wire resting in said plunger, said casing having a slot therein, and a stud 25 on said plunger engaging said slot to limit the movement of said plunger and said wire.

36. In a stringing machine, a rotor having a plurality of article engaging recesses therein, and having a plurality of pockets adjacent to said recesses, means to rotate 30 said rotor, said recesses and pockets being so constructed and arranged that said articles will be received in said recesses flat against the face of the rotor and will pass, during continued rotation of said rotor, into 35 said pockets and be held therein in a position angular to the face of said rotor.

37. In a stringing machine, an inclined rotor having a plurality of article engaging recesses therein, and having a plurality of pockets adjacent to said recesses, means to rotate 40 said rotor, said recesses and pockets being so constructed and arranged that said articles will be received in said recesses flat against the face of the rotor and will pass, during continued rotation of said rotor, into 45 said pockets and be held therein in a position angular to the face of said rotor.

In testimony whereof, I have signed my name to this specification.

EDWARD B. CARTER.
